UNITED STATES PATENT OFFICE.

JOSEPH H. TALBOT MARTIN, OF CHICAGO, ILLINOIS.

DESIGN FOR A LAMP-FIXTURE.

SPECIFICATION forming part of Design No. 32,572, dated April 24, 1900.

Application filed February 19, 1900. Serial No. 5,853. Term of patent 7 years.

To all whom it may concern:

Be it known that I, JOSEPH H. TALBOT MARTIN, a citizen of the United States, and a resident of Chicago, in the county of Cook and State of Illinois, have invented and produced a new and original Design for a Lamp-Fixture, of which the following is a specification.

In the accompanying drawing the figure is a side view of a lamp-fixture embodying my design.

A lamp-fixture of my design comprises a substantially-spherical reservoir A, outwardly and upwardly extending members A', the upper ends of which are bent inwardly toward each other, ornamental braces or brackets A², which connect the reservoir A and the members A', and scrollwork A³, which extends upwardly from and connects the members A'

adjacent to their free ends. The brackets A² 20 consist of scrolls, elements of which are disposed to form the character shown at a. The scroll A³ consists of two downwardly-diverging sections, elements of each of which are disposed to form the character shown at a'. 25 At its upper end the scroll A³ forms a ring or loop, within which is the character shown at a².

I claim—

The design for a lamp-fixture, substantially as herein shown and described. 30

In testimony that I claim the foregoing as my invention I have hereunto set my hand, this 16th day of February, 1900, in the presence of two witnesses.

J. H. TALBOT MARTIN.

Witnesses:

H. M. GRIER,

J. H. FRAMBACH.
